UNITED STATES PATENT OFFICE.

PATRICK KENNEDY, OF GLOUCESTER, MASSACHUSETTS.

DESIGN FOR A MONUMENT.

SPECIFICATION forming part of Design No. 11,948, dated August 17, 1880.

Application filed July 23, 1880. Term of patent 3½ years.

To all whom it may concern:

Be it known that I, PATRICK KENNEDY, of Gloucester, of the county of Essex and State of Massachusetts, have invented or produced 5 a new ornamental Design for a Monument; and I do hereby declare the same to be described in the following specification and represented in the accompanying drawings, of which—

10 Figure 1 is a front elevation, and Fig. 2 a perspective view, of a monument embracing the said design.

15 The plinth A is quadrilateral, with vertical rectangular sides, and slopes on its top downward from each side of the base B. The base B, also quadrilateral and sloping, as shown, is surmounted by the shaft or die C, which is the frustum of a quadrangular pyramid, provided on each face with a projecting tablet, D, 20 formed in manner as represented. Resting on the top of the shaft or die is the cap E, pedimented on each face and crowned by a quadrilateral pyramid, and its quadrangular base

b, each side of which is vertical, or it may be slightly inclined in the plane of the face of the die. The face of each pediment of the cap I usually ornamented, as shown, with a fleur-de-lis flanked by fretted arms, all being incised in the said face.

25 I claim—

1. The monumental design, substantially as represented, of the base, the tableted die, and its cap.
2. The pyramidal die with its projecting tablets, all formed and arranged as represented.
3. The cap pedimented and crowned with the pyramid and its quadrilateral base, as shown.
4. The monumental design, substantially as represented, of the plinth, the base, the tableted die, and its pedimented cap.

30 40 PATRICK KENNEDY.
